UNITED STATES PATENT OFFICE.

HARRIETT A. CRAWLEY, OF BROOKSVILLE, KENTUCKY, ASSIGNOR OF ONE-HALF TO
ORVIL CUMMINS, OF FALMOUTH, KENTUCKY.

MILK-CAN.

1,308,047.

Specification of Letters Patent.

Patented July 1, 1919.

Application filed April 28, 1916. Serial No. 94,166.

To all whom it may concern:

Be it known that I, HARRIETT A. CRAWLEY, a citizen of the United States, residing at Brooksville, in the county of Bracken and 5 State of Kentucky, have invented certain new and useful Improvements in Milk-Cans; and I do hereby declare the following to be a full, clear, and exact description of the invention, such as will enable others 10 skilled in the art to which it appertains to make and use the same.

This invention relates to new and useful improvements in milk cans and the principal object of the invention is to provide a can 15 having a smooth interior and a mouth of greater width than the body of the can.

Another object of the invention is to provide a sanitary milk can which may be readily cleaned and in which the covers are so 20 arranged as to form a substantially air tight joint in order to exclude dust and germs from the can.

A still further object of the invention is 25 to provide a can having an interior cover and an exterior cover so as to form a dead air space between the contents and the surrounding air. The said interior cover consisting of a flanged cover portion having the inverted frusto-conical crown or head portion which is adapted to engage the inclined walls of the can and a flange on the 30 head portion or crown by means of which the same is attached to the cover.

A still further object of the invention is 35 to provide a handle which is formed integral with the flange and extends transversely of the inner cover to permit the same to be readily removed.

With these and other objects in view, the 40 invention consists in the novel combination and arrangement of parts which will be fully set forth in the following specification and accompanying drawing, in which:—

Figure 1 is a front view in elevation of a milk can constructed in accordance with this invention,

Fig. 2 is a vertical sectional view on line 50 2—2 of Fig. 1, and

Fig. 3 is a perspective view of the inner cover illustrating in detail the formation of the handle.

Referring to the drawing, the numeral 1

designates the main body of the milk can 55 which is cylindrical in cross section and provided at its upper end with the inverted frusto-conical portion 2. A frusto-conical base 3 is formed at the lower end of the body 1 and riveted or otherwise secured at 60 a point where the base joins the body 1 is the bottom 4.

The outer cover is designated generally by the numeral 5 and consists of a disk 6 having a flange 7 formed at its lower end, 65 the outer faces of which are inclined as clearly shown in Fig. 2 to conform to the inclination of the inverted frusto-conical member or portion 2 of the can body. The flange 7 as illustrated in the drawing wedges 70 downwardly into the mouth of the can and against the inner face of the inverted frusto-conical portion 2 and thus forms a substantially air tight joint which will exclude dust and germs from the interior of the can. 75 The cover 5 is hinged as at 8 to the upper edge of the portion 2 and carries a suitable hinged hasp 9 which is slotted to receive the staple 10 secured to the extension 2 at a point diametrically opposite the hinge 8. It will thus be seen that when the hasp is closed in the manner illustrated in the drawing, a padlock may be slipped through the staple 10 and will effectively hold the cover 80 against opening.

The inner cover of the device consists of the cover member 11 provided with the flange 12 which is adapted to fit within the body 1 and this cover member 11 has riveted or otherwise secured thereto the crown member designated generally by the numeral 13 consisting of the inverted frusto-conical body 14 having the inturned flange 15 formed at its lower edge. Formed integral with and extending transversely of the flange 15 is a handle designated by the numeral 16 which is struck up as clearly illustrated in Fig. 3 and provides means for positioning and removing the cover.

In use it will be seen that when the can has been filled the cover 11 is placed in the position as illustrated in Fig. 2 and thus a tight joint will be made between the crown and the portion 2 which will exclude dust and other foreign matter from the interior of the can. It will also be seen that a substantially air tight joint is formed and when

- the cover 5 is closed as illustrated in Fig. 2, the flange 7 will wedge into the inverted frusto-conical portion 2 of the body 1 and form a seal which will protect the cover 11.
- 5 It will also be noted that the construction of the handle 16 provides an exceedingly strong and durable structure which is not apt to get out of order and may be easily and cheaply constructed.
- 10 While in the foregoing there has been shown and described the preferred embodiment of this invention, it is to be understood that such changes may be made in the combination and arrangement of parts as 15 will fall within the spirit and scope of the appended claim.

What I claim is:—

Copies of this patent may be obtained for five cents each, by addressing the "Commissioner of Patents, Washington, D. C."

In a milk can of the class described, a cover including an upper and a lower disk arranged in abutting relation, means securing the disks together, the edges of the disks being bent angularly in opposite directions to provide flanges for engaging the walls and neck of the milk can, and a handle formed integral with and struck up from the upper disk, as and for the purpose specified. 20 25

In testimony whereof I affix my signature in presence of two witnesses.

HARRIETT A. CRAWLEY.
